UNITED STATES PATENT OFFICE

1,983,340

AUTOMATIC CUT-OFF DEVICE

James L. Breese, Jr., Santa Fe, N. Mex., assignor
to Oil Devices Corporation, Chicago, Ill., a cor-
poration of Illinois

Original application May 14, 1927, Serial No.
191,296. Divided and this application February
15, 1930, Serial No. 428,845

7 Claims. (Cl. 137—68)

My invention relates to a fuel control means for a hydrocarbon burner and has for particular purpose the provision of means for controlling the flow of a liquid hydrocarbon fuel. Another purpose is the provision of a thermostatically controlled fuel regulation. Another purpose is the provision of a thermostatic control, with means for cutting off the supply of fuel when the temperature rises above a predetermined point, and 5 for supplementally increasing the normal supply of fuel when the temperature drops below a predetermined point. Another object is the provision of an improved overflow control. Other objects will appear from time to time in the course of the 10 specification and claims.

The present application is a division of my co-pending application No. 191,296, filed on May 14, 1927, now Patent No. 1,845,999.

I illustrate my invention more or less diagrammatically in the accompanying drawings, wherein—

Figure 1 is a vertical section of my device with parts in elevation and with the electric circuits diagrammatically shown;

25 Figure 2 is a plan view of the control device proper, with the cover removed;
Figure 3 is a section on the line 3—3 of Figure 2;
Figure 4 is a section on the line 4—4 of Figure 2;
Figure 5 is a section on the line 5—5 of Figure 30 3; and

Figure 6 is a section on the line 6—6 of Figure 3.

Like parts are indicated by like symbols throughout the specification and drawings.

A generally indicates the outer shell or drum of a hydrocarbon burner, A¹ being the upper or combustion chamber. A² is a transverse partition centrally apertured as at A³. Seated in the aperture A³ is the mixing drum or chamber A⁴ with the concave bottom A⁵. The drum is provided 40 with a plurality of small apertures A⁶ spaced in general uniformity about the intermediate and lower portion of its walls. Adjacent the upper edge of the walls is a row A⁷ of larger and upwardly inclined apertures. A⁸ is an upwardly and 45 inwardly inclined flange projecting inwardly from the upper edge of the drum A⁴. A⁹ is a distributor member in the center of the bottom member. A⁵ and A¹⁰ are apertures in the walls thereof. A¹¹ indicate air inlet apertures about the lower edge 50 of the drum A and A¹² are any suitable air inlets whereby air may pass through the transverse partition A¹⁴ which underlies the mixing chamber A⁴.

B indicates an oil supply line which extends from any suitable oil supply to the float chamber 55 generally indicated as C. B¹ is an oil line extend-

ing from said float chamber and communicating, by the elbow B² with the bottom A⁵ of the mixing chamber A⁴. B³ is a gas line which extends into the union member B⁴ and axially along the pipe B¹ to terminate as at B⁵ within the distributor member A⁹ in the mixing chamber at a level above the normal level of admittance of the liquid fuel. B⁶ is a bushing member adapted to receive the fuel line B¹. It may be secured in relation to the burner for example by the set screw B⁷ in the hollow member B⁸ which is secured as at B⁹ to the drum A.

Referring more particularly to the flow chamber, as shown in Figures 2 and following the fuel line B communicates with the initial admission chamber C¹ in which is positioned the strainer C² yieldingly thrust upwardly by the spring C³ against an upper abutment C⁴. C⁵ is a removable screw threaded plug which engages the spring C³ and which permits removal of the strainer and access to the chamber C¹. C⁶ is a fuel passage extending upwardly from said chamber and controlled by the valve member D. This valve member is pivoted to the end of a lever D¹ which lever is in turn pivoted as at D² closely adjacent its connection with the valve member D. Its opposite end is downwardly turned as at D³ and is secured to the float D⁴. It will be understood that when the level of oil in the float chamber is below the predetermined normal oil flows through the passage B and the passage C⁶ and escapes over the ledge C⁷ to the float chamber proper indicated as C⁸. D⁵ is a shield, associated with the valve D, and adapted to prevent any substantial upward gush of the inflowing fuel.

As shown in Figure 5 the ledge C⁷ is bounded at one end by a raised portion C¹⁰ through which extends the outlet or overflow passage C¹¹.

E indicates a transverse rod upon which is pivoted the weight E¹. Preferably formed integrally with such weight is the lever E² to the end of which is pivoted a stem E³ extending downwardly through the passage C¹¹. It terminates at its lower end in the hook E⁴ to which may be secured the bail E⁵ of the overflow control bucket E⁶. 100 E⁷ is a laterally projecting lug herein shown as associated with the lever E², and E⁸ is a corresponding lateral projection mounted upon the lever E⁹ at the opposite side of the rod E. It will be understood that in case the float chamber 105 becomes so filled that oil flows downwardly through the overflow passage C¹¹ and fills the bucket, the weight of the bucket will trip the counterweight E¹ and will cause it to take the position shown in dotted line in Figure 3. In 110

such case the projection E⁸ will contact the lever D¹ and rotate it about its pivot D² in such wise as to close the valve D and prevent further admission of fuel. On the other hand, if the trip 5 bucket E⁶ is removed from the hook E⁴ the counterweight E¹ will drop to the position shown in dotted line in Figure 4. In such case the lug E⁷ will contact the lever D¹ and close the valve D. Thus no fuel can flow into the float chamber 10 unless the overflow bucket is in position, and no fuel can flow into the chamber when the overflow bucket is sufficiently full to tilt the weight E¹ to the right of the position in which it is shown in full line in Figures 3 and 4. When the 15 overflow bucket E⁶ is in position, and is not so filled, it is normally held, by the weight E¹, in the full line position shown, being drawn up against the bottom of the float chamber.

The weight E¹ is kept in proper position in relation to the lever D, for example by the spacing sleeves E¹⁰E¹¹ on the pin E. E¹² is a semi-circular guard to protect the overflow bucket E⁶.

The fuel line B¹ is connected with a downward projection or boss G positioned on the side of the 25 float chamber opposite to the inlet chamber C¹. It is provided with an aperture G¹ in opposition to the end of the line B¹, access to which may be had by removal of the square ended screw G², as shown in Figure 3. In communication with the 30 space G¹ are two ducts G³G⁴ which in turn communicate with the vertical apertures G⁵G⁶. Screwthreaded in these apertures are the valve cylinders G⁷ in the lower ends of which are screwthreaded the valve seats G⁸. G⁹G¹⁰ are 35 valve stems slidable in the bearing members G¹¹ which are screwthreaded into the upper ends of the sleeves G⁷. The upward movement of said stems is limited by a pin or stop G¹², adjustment of the valve excursion being obtainable by rotation of the screwthreaded members G¹¹. The 40 valve cylinders G⁷ are apertured as at G¹³ to receive the oil passing through the circular screen members G¹⁴ which are held in position by tension springs G¹⁵, one end being frictionally engaged by the threaded members G¹¹. Each valve 45 cylinder G⁷ is provided with an air hole G¹⁶ above the fuel level. G¹⁷ is an air vent member extending upwardly from the passage G¹ to the point well above the highest possible fuel level.

50 I prefer to render the valves G⁹G¹⁰ responsive to temperature conditions. The thermostatic control may be based upon temperatures adjacent the burner or upon local or room temperatures taken elsewhere, depending upon the needs of 55 the particular installation. Referring to the diagrammatic portion of Figure 1 H indicates the house current which may for example be a 110 volt current. H¹ is the primary coil of a transformer, in such house circuit and H² is a secondary coil of such transformer. H³ is a conductive line extending from one end of said secondary coil H² to the terminal H⁴. H⁵ is a conductive line extending from the opposite end of the secondary coil to any suitable thermostatic leaf H⁶. Opposed to such leaf are the contacts H⁷ and H⁸. When the temperature rises to a predetermined point the leaf H⁶ will touch one of said contacts, for example H⁷ and the six volt current will pass through such contact along the conductive line H⁹ to a terminal H¹⁰. On the contrary when the temperature drops to a predetermined degree a circuit will be closed through the opposite contact H⁸ and the six volt current will pass along the conductive line H¹¹ to the terminal H¹².

I I¹ are generally similar bi-metallic thermostatic strips which are adapted to flex in opposite directions in response to similar changes in temperatures. I² and I³ are resistance members or coils associated respectively with the leaves I and I¹. 80

The leaves are apertured at their outer ends as at I¹⁴ to receive the upper ends of the valve stems G⁹ and G¹⁰. The cross pins G¹⁹G²⁰ of said valve stems engage the upper surface of the thermostatic leaves. 85

It will be understood that when the leaf H⁶ deflects to the right, as shown in Figure 1, and closes the circuit through the contact H⁷ and conductor H⁹ the circuit is continued through the resistance I² by means of the conductive connection I⁶ from the terminal H¹⁰ to the resistance and the conductive connection I⁷ from the resistance to the return terminal H⁴. Similarly, if the leaf H⁶ deflects in the opposite direction, in response to a drop in temperature, the circuit is closed through the line H¹¹ and the terminal H¹² and passes thence by the conductive line I⁸ to the resistance I³ and thence by the conductive line I⁹ to the return terminal H⁴. 90

When the leaf H⁶ is in intermediate position and neither resistance is actuated, the leaf I and the resistance I² will be in the position shown in dotted line at the right of Figure 6 and the valve stem G¹⁰ will be upwardly withdrawn to permit 105 a flow of fuel through the aperture G⁶ and the duct G⁴ into the fuel line B¹. As long as the temperature remains within the predetermined range, fuel will be supplied to the fuel line B¹ through but a single duct. However when the 110 temperature exceeds the predetermined normal and the resistance I² is heated, the leaf I flexes to the position shown in full line at the right of Figure 6 and the valve G¹⁰ is permitted to drop into closed position. 115

If the temperature drops below the desired normal range, the resistance I² is of course not heated and the valve stem G¹⁰ remains in open position. But the resistance I³ becomes heated and the leaf I¹ flexes upwardly into the position shown in 120 dotted line in Figure 6. This flexure of the leaf causes it to lift the valve stem G⁹, thus permitting fuel to flow to the line B¹ through the duct G³. The valve unit is protected by a cover K fastened to the float chamber C by screws K¹. 125

Referring for example to Figure 1, it will be seen that the float chamber and the control mechanism make it impossible for the level of fuel within the mixing chamber A⁴ to reach the lowest air apertures A⁶. This is important, and it is 130 an important feature of my device that I so locate the float chamber in relation to the chamber A⁴ that under no circumstances can the fuel level in the chamber A⁴ approach the air inlets. In fact I so position my float chamber that the chamber 135 A⁴ can never overflow and can only receive fuel to a relatively small depth in the bottom of the chamber.

It will be realized that whereas I have shown and described a practical and operative device, 140 nevertheless many changes might be made in the size, shape, number and disposition of parts without departing from the spirit of my invention. I therefore wish my description and drawings to be taken as in a broad sense diagrammatic and illustrative rather than as limiting me to my specific showing. 145

I claim:

1. A constant level chamber having an inlet, means for normally maintaining a constant level 150

- therein including a valve to control said inlet, means for stopping the delivery of liquid into the chamber when the liquid therein has reached a predetermined level, said means including an actuating member for said valve, an overflow bucket secured to said member and receiving excess liquid from the chamber, said actuating member having a weight thereon movable past dead center position to quickly close the valve. 5
2. A constant level chamber having an inlet, means for normally maintaining a constant level therein including a valve to open or close the liquid inlet, an actuation member cooperating with said valve, said member having detachable connection to an overflow bucket receiving excess liquid from the chamber, and arranged to close the valve either upon overflow of liquid into the bucket or detachment of the bucket from the actuating member. 10
3. A constant level chamber having an inlet, means for normally maintaining a constant level therein including a valve to open or close the liquid inlet, an actuating member cooperating with said valve, said member having detachable connection to an overflow bucket receiving excess liquid from the chamber and arranged to close the valve upon overflow of the liquid into the bucket and a weight on the actuating member movable to quickly close the valve either upon overflow into the bucket or detachment of the bucket. 15
4. A constant level chamber having an inlet, means therein for maintaining a constant level including a valve and a lever pivoted adjacent said valve, means for stopping the delivery of
- liquid into the chamber when the liquid therein has reached a predetermined level, comprising rotatable means operable by the liquid at said predetermined level on the opposite side of the pivot for engaging the lever to close the valve. 20
5. A constant level chamber having an inlet and an overflow duct leading therefrom, means therein for maintaining a constant level including a valve for said inlet, a bucket removably supported beneath said duct and receiving liquid therefrom upon overflow to close the valve, and means connected to the valve and operable upon removal of said bucket to close said valve. 25
6. A constant level chamber having an inlet and an overflow duct leading therefrom, means therein for maintaining a constant level including a valve for said inlet, a bucket removably supported beneath said duct and receiving liquid therefrom upon overflow, and common means cooperating with said valve to close the same upon overflow into the bucket or upon removal of the bucket from its support. 30
7. A constant level chamber having an inlet, means for maintaining a constant level therein, including a valve and a lever pivoted adjacent said valve means for stopping the delivery of liquid to the chamber when the liquid therein has reached a predetermined level, comprising rotatable means operable by the liquid at said predetermined level on the opposite side of the pivot engaging the lever to close the valve, said means including a weight movable beyond dead center to quickly close said inlet valve. 35
